SLUG-CASTING MACHINE

George P. Kingsbury, Hollis, N. Y., assignor to
Mergenthaler Linotype Company, a corpora-
tion of New York

Application February 2, 1938, Serial No. 188,223

20 Claims. (Cl. 199—49)

This invention relates to slug casting machines, such as those of the general organization represented in U. S. Letters Patent No. 436,532 to O. Mergenthaler, wherein circulating matrices 5 are released from a magazine in the order in which their characters are to appear in print and then composed in line, the composed line transferred to a vertically movable transporter or "first elevator" which descends from its line receiving position to present the line before the face of a slotted mold, the mold filled with molten metal to form a slug or type bar against the matrices which produce the type characters thereon, the transporter elevated to a line transfer position where the matrices are transferred from the transporter to a distributing mechanism which returns them to the magazine from which they started, and the transporter finally lowered to its line receiving position. 10 In such machines, the transporter, as it descends from its line receiving position, is arrested at one or another of different levels depending on the size of the characters borne by the matrices in the composed line, and irrespective of 15 the level at which the transporter is so arrested, the upper faces of the lower inner ears on the matrices are positioned slightly below the level of an aligning lip on the face of the mold. Thereafter, the mold is moved forward to press 20 the front face thereof against the composed line, and then the transporter is urged upwardly to press the matrix ears against the mold lip to bring about the customary face alignment of the matrix characters with the mold slot. 25 The vertical movements of the transporter are effected by a cam on the main drive shaft of the machine, and to enable the same active portion of the cam to bring about the slight upward movement of the transporter during the matrix aligning operation, the train of connections leading 30 from the cam to the transporter includes a connecting link embodying a compression spring which yields when the ears on the matrices engage the mold lip. 35 Inasmuch, however, as the same active portion of the cam brings about the slight upward matrix aligning movement of the transporter from all of the levels at which it may be arrested, it (the transporter) tends to rise to the same common 40 level in all cases. In consequence, when the transporter is urged upwardly from its lowermost level and its ascent arrested by the engagement of the matrix ears with the mold lip positioned slightly above that level, the compression spring 45 is subjected to a greater degree of compression 50

than it is when the transporter is urged upwardly from a higher level and its ascent arrested by the engagement of the matrix ears with the mold lip positioned slightly above that higher level.

This variation in the compression of the spring 5 is open to the objection that, when the spring is made sufficiently strong to insure proper alignment of the matrix characters when the transporter is urged upwardly from its uppermost level, the pressure exerted between the matrix 10 ears and the mold lip when the transporter is urged upwardly from its lowermost level sometimes causes undue wear and damage to the ears. And, conversely, when the spring is made only 15 strong enough to insure proper alignment of the matrix characters without undue wear and damage on the matrix ears when the transporter is urged upwardly from its lowermost level, it sometimes fails to exert the pressure necessary to bring about the proper alignment of the matrix 20 characters when the transporter is urged upwardly from its uppermost level, this being particularly true after the machine has been in use 25 over an extended period.

The present invention contemplates an arrangement whereby substantially the same pressure is exerted between the ears on the matrices and an aligning lip on the mold irrespective of the level from which the transporter is urged upwardly for aligning purposes; and to this end, 30 means are provided which operate automatically to maintain the compression of the spring at substantially the same value during the aligning operation. More specifically, means are provided for automatically maintaining the effective 35 length of the connecting link normal when the transporter is arrested at its lowermost level and for automatically increasing the effective length 40 of the connecting link when the transporter is arrested at a higher level, such increase being substantially equal to the distance between the lowermost level and said higher level. Under these conditions, when the transporter is urged upwardly from either level, the compression 45 spring is subjected to the same pressure, which may be so regulated as to insure proper alignment without undue wear or damage to the ears of the matrices.

As before stated, the transporter, after the slug or type bar has been cast, is elevated by the 50 cam to a line transfer position, and to insure that the transporter is not lifted beyond this position when the effective length of the link is increased, means are also provided for restoring the link to its normal effective length before 55

the transporter reaches its line transfer position.

For a more detailed description of the invention, reference may be made to the accompanying drawings wherein the invention is shown merely by way of example and in preferred form. Obviously, however, many variations and modifications may be made therein which will still be comprised within its spirit, and it is to be understood, therefore, that the invention is not to be limited to any specific form or embodiment, except insofar as such limitations are specified in the appended claims.

Referring to the drawings:

Fig. 3 is a front elevation, partly in section, of a portion of the transporter or first elevator with the spring pressure control mechanism associated therewith;

Fig. 4 is a side view, partly in section, showing the position assumed by the connecting link when the transporter is arrested at its intermediate casting level;

Fig. 5 is a side elevation, partly in section, showing the position assumed by the connecting link when the transporter is arrested at its uppermost casting level;

Fig. 6 is a side elevation, partly in section, showing the means employed for operating the spring pressure control mechanism;

Fig. 7 is a plan view, in section, taken along the line 7—7 of Fig. 6;

Fig. 8 is a side view, partly in section, showing the relationship between a composed line of matrices and the mold prior to a slug casting operation; and

Fig. 9 is a side view, partly in section, showing the position assumed by the connecting link when the transporter is arrested at its lowermost casting level.

After composition, a line of matrices 10 is delivered to the line transporter or first elevator 11 which descends to position it before a casting slot 12 of a mold 13 carried by a rotatable mold disk 14.

As usual, the mold disk 14 is provided with a number of molds (usually four) to enable slugs bearing characters of different point sizes to be cast, and it is adapted to be manually adjustable so that any one of the molds may be brought into action to the exclusion of the others. In Fig. 8, there is shown a mold of the kind adapted to cast slugs bearing characters up to 36 pt., which mold is provided with two superposed aligning lips 15 and 16 whose lower faces are spaced predetermined distances from the so-called constant line 17 of the mold. The lower lip 15 is used to align the characters on the matrices with the mold slot 12 when the mold is adjusted for matrices bearing characters between 5½ pt. and 14 pt., and the upper lip 16 is utilized to align the characters on the matrices with the mold slot 12 when the mold is adjusted for matrices bearing characters between 14 pt. and 36 pt. Molds adapted to cast slugs from matrices bearing characters above 36 pt. are provided with a single aligning lip corresponding to the upper lip 16 but made thinner, as indicated by the dotted lines in Fig. 8, so that its lower face will be spaced a predetermined lesser distance from the constant line 17 of the mold than the lower face of the lip 16.

In casting slugs from matrices bearing characters from 14 pt. to 36 pt., the transporter 11 as it descends to position the composed line before the mold slot 12 is arrested at an intermediate level, as determined by the direct engagement of an arresting pin 20 carried thereby with the top face of an interponent 21 pivotally mounted on the top of the stationary vise frame 23; and at this intermediate level, the upper faces of the lower inner ears 24 on the matrices are slightly below the lower face of the upper aligning lip 16 on the mold, all as is shown by full lines in Fig. 8. In the event, however, the matrices bear characters from 5½ pt. to 14 pt., the interponent 21 is swung out of the way and the transporter 11 descends to its lowermost level, as determined by the direct engagement of the arresting pin 20 with the top face of the vise frame 23; and at this lowermost level, the upper faces of the lower inner ears 24 on the matrices would be positioned slightly below the level of the lower face of the lower aligning lip 15 on the mold. On the other hand, when the matrices in the line bear characters above 36 pt., a second (supplemental) interponent 22 is swung into operative position above the main interponent 21, as shown by the dotted lines in Fig. 8, to arrest the descent of the transporter 11 at its uppermost level, as determined by the direct engagement of the arresting pin 20 with the top face of the upper interponent 22; and at this uppermost level, the upper faces of the lower inner ears 24 on the matrices are positioned slightly below the level of the lower face of the thinner aligning lip on the mold selected for such larger matrices. If more detailed information is desired about this feature of arresting the transporter 11 at different levels, reference may be had to the pending application of Richard R. Mead, Serial No. 161,253, filed August 27, 1937, or to the U. S. Patent No. 1,595,947 granted to D. S. Kennedy.

After the transporter 11 has been arrested at one or another of its casting levels, the mold disk 14 is advanced to press the front face of the mold 13 against the composed line of matrices 10, and the transporter 11 is then urged upwardly to press the matrix ears 24 up against the corresponding mold lip to bring about the customary face alignment of the matrix characters with the mold slot 12. Then the mold slot is filled with molten metal to form the type bar or slug against the matrices which produce the type characters thereon. Thereafter, the mold disk 14 is moved back to its rotating position, and the upward pressure on the transporter 11 is released to break the engagement between the matrix ears and the mold lip, after which the transporter is raised, as usual, to its upper transfer position where the line is transferred to the distributing mechanism which returns the matrices to their usual place of storage.

The vertical movement of the transporter 11 is effected by a cam 25 fixed to the main drive shaft 26 of the machine. To this end (see Figs. 1 and 3), the lower end of the transporter 11 is provided with a hub portion 27 in which a pivot pin 28 is journaled. The upper eye member 29 of a connecting link 30 is pivotally mounted on the pivot pin 28, and the lower eye member 31 thereof is pivotally mounted on a stud 32 carried by the forward end of a fore-and-aft lever 33. At its rear end, the fore-and-aft lever 33 is pivotally mounted on a rod 34 carried by the main frame of the machine, and is provided with an upstanding arm 35. The upper end of the arm 35 is provided with a roller stud 37 contacted by

a set screw 36 carried by a lug 38 projecting forwardly from the central portion of a vertically disposed lever 39. The lever 39 is also pivotally mounted on the rod 34 and is provided at its upper end with a roller 40 maintained by the weight of the transporter in contact with the periphery of the cam 25. As the cam rotates in the direction of the arrow during the normal operation of the machine, a portion 25a imparts a slight upward movement to the transporter during the matrix aligning operation through the train of connections just described.

The connecting link 30 (Fig. 2) comprises a vertically disposed cylinder 41 having a gland 42 screwed into the lower end thereof and a somewhat similar gland 43 screwed into the upper end thereof. The upper gland 43 is provided with a centrally disposed nut portion 44 threaded to a stud 45 carried by the upper eye member 29. The lower gland member 42 is provided with a centrally disposed opening, and a threaded stud 47 carried by the lower eye member 31 extends upwardly in free fashion through the opening and into the cylinder 41, where it is threaded to a collar 48 which, while free to move upwardly and downwardly within the cylinder, is held against rotation by a key 49. A compression spring 55 is positioned in the cylinder 41 between the upper face of the collar 48 and the lower face of the upper gland 43. By adjusting the position of the lower gland 42 and the superimposed collar 48, minor adjustments in the strength of the spring may be effected; and to lock the parts after adjustment has been made, the lower eye member 31 is provided with a leaf spring 50 which is adapted and arranged to engage one of a number of spaced notches 51 cut in the lower gland 42.

As the outer end of the fore-and-aft lever 33 moves upwardly under the influence of the portion 25a of the cam 25, the transporter 11 is raised to carry the ears 24 on the matrices into engagement with an aligning lip on the mold in use, and as the ears engage the lip, the spring 55 yields and is compressed, but when compressed it exerts the required pressure between the ears and the lip to effect the necessary aligning operation.

In accordance with the present invention, means are provided to maintain the spring pressure thus exerted between the matrix ears 24 and the mold lip substantially the same irrespective of the level at which the transporter 11 is arrested. As shown more clearly in Figs. 4, 5, and 9, the opening 56 in the upper eye member 29, through which the pivot pin 28 passes, is elongated in a vertical direction. In addition, the upper eye member 29 is provided with a vertical recess 57 to accommodate a toothed locking pawl 59 made fast to the pivot pin 28 and which is adapted and arranged to engage a correspondingly toothed portion 58 of the eye member. A small pull spring 60, connected at one end to a collar 61 secured to the pivot pin 28 and at its other end to the transporter 11, tends to rock the pin forwardly and hold the pawl 59 resiliently against the front wall of the recess 57 (see Fig. 9). The pivot pin 28 is also provided with a depending actuating arm 62, which is arranged to be operated by an arm 64 rising from a small horizontal rock shaft 63, as shown more clearly in Fig. 3. The rock shaft 63 is journaled in a bearing bracket 65 secured to the lower portion of the inner face of the cam plate or slug lever device 66a carried by the transporter 11. In a manner subsequently to be described, a crank

arm 67, depending from the rock shaft 63, is adapted and arranged to be operated by a long lever 68 pivotally secured to the vise frame 23. This lever 68 is in turn operated by the forward movement of the mold disk 14 against the action of a spring 46 through a horizontal push rod 70 slidably mounted in a cylinder 71 carried by a bracket 72 which is fastened to the vise frame 23. The push rod 70 acts through a compression spring 73 which yields in the event of any undue resistance in the operation of the parts to prevent damage thereof.

The operation of the parts will now be clear: When the transporter 11 is allowed to descend to its lowermost level, as determined by the direct engagement of the pin 20 with the top face of the vise frame 23, the pivot pin 28 which connects the upper end of the link 30 to the lower end of the transporter 11 is positioned at the bottom of the elongated opening 56 in the upper eye member 29, the pawl 59 is maintained in its inoperative position by the pull spring 60 as shown in detail in Fig. 9, and the lower end of the long operating lever 68 is positioned above and clear of the crank arm 67. Then, as the mold disk 14 moves forwardly to press the front face of the mold 13 against the composed line of matrices 10 and the transporter rises, the ears 24 on the matrices engage the lower mold lip 15 and so bring about the face alignment of the characters 30 on the matrices with the mold slot 12. As the matrix ears 24 engage the mold lip 15, the spring 55 is compressed and exerts the desired aligning pressure.

In the event, however, that the transporter 11 is arrested at its intermediate casting level, as determined by the direct engagement of the pin 20 with the top face of the lower main interponent 21, the pivot pin 28 becomes positioned midway of the elongated opening 56 in the upper eye member as shown in detail in Fig. 4, and the crank arm 67 becomes positioned behind the lower end of the long operating lever 68 as shown in Fig. 3. Then as the mold disk 14 moves forwardly, the lower end of the operating lever 68 is rocked rearwardly and so rotates the rock shaft 63. As the rock shaft 63 rotates, the arm 64 rising therefrom engages the actuating arm 62 and rotates the pivot pin 28 in the opposite direction to carry the pawl 59 forwardly against the action of the spring 60 into engagement with the toothed portion 58 to lock the pivot pin in its aforesaid midway position to the upper eye member 29, as shown in Fig. 4. Under these conditions, the effective length of the link 30 is automatically increased a distance equal to the thickness of the lower interponent 21, or, in other words, to the distance between the lowermost and the intermediate arresting levels of the transporter. In consequence, as the transporter 11 is urged upwardly from the intermediate level to press the matrix ears 24 against the upper aligning lip 16 on the mold, the spring 55 is subjected to substantially the same degree of compression that it was when the transporter 11 was elevated from its lowermost level to align the matrices against the lower mold lip 15.

As the mold disk 14 moves backwardly, after the casting operation, the long operating lever 68 is rocked back to its initial position by the spring 46 and the pawl 59 is pulled out of engagement with the toothed portion 58 by the spring 60. The disengagement of the pawl 59 from the toothed portion 58 permits the pivot pin 28 to pass to the lower end of the elongated opening 56

as the transporter is raised to its upper line transfer position, and since under these conditions the effective length of the link 30 is restored to normal, the transporter comes to rest in its normal line transfer position.

If now a mold adapted to cast slugs bearing characters above 36 pt. is brought into operative position, and the descent of the transporter is arrested at its uppermost level as determined by the direct engagement of the arresting pin 20 with the top face of the upper supplemental interponent 22, the pivot pin 28 travels to the top of the elongated opening 56 in the upper eye member 29 and the crank arm 67 becomes positioned behind the lower end of the long operating lever 68, although at a slightly higher level. Then as the mold disk 14 moves forwardly and before the cam 25 acts to raise the transporter 11 for aligning purposes, the pivot pin 28 is rotated as above described to carry the pawl 59 into engagement with the toothed portion 58 to lock the pivot pin 28 in its top position to the upper eye member 29, as shown in Fig. 5. Under these conditions, the effective length of the connecting link 30 is automatically increased a distance equal to the combined thickness of both interponents 21 and 22, or, in other words, to the distance between the lowermost and the uppermost levels at which the transporter may be arrested. Thereafter, when the transporter 11 rises to press the matrix ears 24 against the aligning lip on the mold, the spring 55 is subjected to substantially the same degree of compression that it was when the transporter 11 was elevated from either its lowermost or intermediate level in the two preceding instances.

As in the case where the transporter 11 was raised from its intermediate level, the long operating lever 68 is returned to its initial position and the pawl 59 pulled out of engagement with the toothed portion 58 as the mold disk 14 moves backwardly after the slug casting operation, permitting the pivot pin 28 to run back to the lower end of the elongated opening 56 in the upper eye member 29 as the transporter ascends to its upper transfer position.

Having thus described my invention, what I claim is:

1. In a slug casting machine, the combination of a vertically movable transporter for presenting a composed line of character bearing matrices before the face of a slotted mold, means for arresting the descent of the transporter at one or another of different casting levels, means for thereafter subjecting the transporter to pressure to effect the alignment of the characters on the matrices with the mold slot, and means for maintaining the pressure to which the transporter is subjected at substantially the same value irrespective of the level at which the descent of the transporter is arrested.

2. In a slug casting machine, the combination of a vertically movable transporter for presenting a composed line of character bearing matrices before the face of a slotted mold, means for arresting the descent of the transporter at one or another of different casting levels, compressible means for urging the transporter upwardly to align the characters on the matrices with the mold slot, and means for maintaining the compression in said means at substantially the same value irrespective of the level from which said transporter is urged upwardly.

3. In a slug casting machine, the combination of a vertically movable transporter for present-

ing a composed line of character bearing matrices before the face of a slotted mold, means for arresting the descent of the transporter at one or another of different casting levels, a cam controlled lever for urging the transporter upwardly from any one of said levels to effect alignment of the characters with the mold slot, and means for maintaining the pressure exerted by the lever on the transporter during the aligning operation at substantially the same value irrespective of the level from which the transporter is urged upwardly.

4. In a slug casting machine, the combination of a vertically movable transporter for presenting a composed line of character bearing matrices before the face of a slotted mold, means for arresting the descent of the transporter at one or another of different casting levels, a cam controlled lever for urging the transporter upwardly from any one of said levels to effect alignment of the characters with the mold slot, a resilient connecting link interposed between the lever and the transporter, and means for maintaining the pressure exerted by the lever through the link on the transporter during the aligning operation at substantially the same value irrespective of the level from which the transporter is urged upwardly.

5. In a slug casting machine, the combination of a vertically movable transporter for presenting a composed line of character bearing matrices before the face of a slotted mold, means for arresting the descent of the transporter at one or another of different casting levels, a cam controlled lever for urging the transporter upwardly from any one of said levels to effect alignment of the characters with the mold slot, a compression spring interposed between the lever and the transporter, and means for maintaining the compression in the spring during the aligning operation at substantially the same value irrespective of the level from which the transporter is urged upwardly.

6. In a slug casting machine, the combination of a vertically movable transporter for presenting a composed line of character bearing matrices before the face of a slotted mold, means for arresting the descent of the transporter at one or another of different casting levels, a cam controlled lever for urging the transporter upwardly from any one of said levels to effect alignment of the characters with the mold slot, a connecting link having a compression spring interposed between the lever and the transporter, and means for maintaining the pressure exerted by the lever through the spring on the transporter at substantially the same value irrespective of the level from which the transporter is urged upwardly.

7. In a slug casting machine, the combination of a vertically movable transporter for presenting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, a connecting link between the lever and the transporter, and means for automatically adjusting the effective length of the link to accord with the level at which the descent of the elevator is arrested.

8. In a slug casting machine, the combination of a vertically movable transporter for pre-

- senting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, a connecting link between the lever and the transporter, means for automatically adjusting the effective length of the link to accord with the level at which the descent of the elevator is arrested, and means for maintaining said link locked in its adjusted position during the aligning operation.
15. 9. In a slug casting machine, the combination of a vertically movable transporter for presenting a composed line of character bearing matrices before the face of a slotted mold, means for arresting the descent of the elevator at one or another of different casting levels, a cam controlled lever for urging the transporter upwardly from any one of said levels to effect alignment of the characters with the mold slot, a yieldable connecting link between the lever and the transporter, and means for so adjusting the effective length of the link that the yield therein during the aligning operation is substantially the same irrespective of the level at which the descent of the elevator is arrested.
30. 10. In a slug casting machine, the combination of a vertically movable transporter for presenting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, a spring-locked connecting link between the lever and the transporter, and means for so adjusting the length of the link that the yield in the spring during the aligning operation is substantially the same irrespective of the level from which the transporter is urged upwardly.
45. 11. In a slug casting machine, the combination of a vertically movable transporter for presenting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, an intermediate connecting link capable of movement relatively to the transporter, and means for locking the link to the transporter prior to the aligning operation.
60. 12. In a slug casting machine, the combination of a vertically movable transporter for presenting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, a connecting link interposed between the lever and the transporter, and a pawl adapted to so regulate the effective length of the link that the pressure exerted by the lever through the link on the transporter is substantially the same irrespective of the level from which the transporter is urged upwardly.
70. 13. In a slug casting machine, the combination of a vertically movable transporter for presenting a composed line of character bearing matrices before the face of a slotted mold, means for arresting the descent of the transporter at one or another of different casting levels, a cam operated lever for urging the transporter upwardly from any one of said levels to effect alignment of the characters with the mold slot, a connecting link interposed between the lever and the transporter, and a pawl adapted to so regulate the effective length of the link that the pressure exerted by the lever through the link on the transporter is substantially the same irrespective of the level from which the transporter is urged upwardly.
75. 14. In a slug casting machine, the combination of a vertically movable transporter for presenting a composed line of character bearing matrices before the face of a slotted mold, means for arresting the descent of the transporter at one or another of three different casting levels, a cam operated lever for urging the transporter upwardly from any one of said levels to effect alignment of the characters with the mold slot, a connecting link interposed between the lever and the transporter, means for permitting relative movement between the link and the transporter when the descent of the transporter is arrested, and means for preventing relative movement between the transporter and the link during the aligning operation.
15. 15. In a slug casting machine, the combination of a vertically movable transporter for presenting a composed line of character bearing matrices before the face of a slotted mold, means for arresting the descent of the transporter at one or another of three different casting levels, a cam operated lever for urging the transporter upwardly from any one of said levels to effect alignment of the character with the mold slot, a connecting link interposed between the lever and the transporter, means for permitting relative movement between the transporter and the link when the transporter is arrested at either of the two upper levels, and means for preventing relative movement between the transporter and the link as the transporter is urged upwardly during the aligning operation from either of the two upper levels.
30. 16. In a slug casting machine, the combination of a vertically movable transporter for presenting a composed line of character bearing matrices before the face of a slotted mold, means for arresting the descent of the transporter at one or another of three different casting levels, a cam operated lever for urging the transporter upwardly from any one of said levels to effect alignment of the characters with the mold slot, a connecting link interposed between the lever and the transporter, means for permitting relative movement between the transporter and the link when the transporter is arrested at either of its two upper levels, and means for locking the transporter to the link before the aligning operation and for unlocking the transporter from the link after the aligning operation.
45. 17. In a slug casting machine, the combination of a vertically movable transporter for presenting a composed line of character bearing matrices before the face of a slotted mold, means for arresting the descent of the transporter at any one of three different casting levels, a cam operated lever for urging the transporter upwardly from any one of said levels to effect alignment of the characters with the mold slot, a connecting link interposed between the lever and the transporter, means for permitting relative movement between the transporter and the link when the descent of the transporter is arrested at either of the two upper levels, and means responsive to a periodically moving element of the machine for locking and unlocking the transporter to the link before and after the transporter is urged upwardly from either of the two upper levels.
60. 18. In a slug casting machine, the combination of a mold disk having a slotted mold, a vertically movable transporter for presenting a composed line of character bearing matrices before the face of the mold, means for arresting the descent of the transporter at any one of three casting levels, a cam operated lever for urging the transporter upwardly from any one of said levels to effect alignment of the characters with the mold slot, a connecting link interposed between the lever and the transporter, means for permitting relative movement between the transporter and the link when the descent of the transporter is arrested at either of the two upper levels, and means responsive to a periodically moving element of the machine for locking and unlocking the transporter to the link before and after the transporter is urged upwardly from either of the two upper levels.
70. 19. In a slug casting machine, the combination of a mold disk having a slotted mold, a vertically movable transporter for presenting a composed line of character bearing matrices before the face of the mold, means for arresting the descent of the transporter at any one of three casting levels, a cam operated lever for urging the transporter upwardly from any one of said levels to effect alignment of the characters with the mold slot, a connecting link interposed between the lever and the transporter, means for permitting relative movement between the transporter and the link when the descent of the transporter is arrested at either of the two upper levels, and means responsive to a periodically moving element of the machine for locking and unlocking the transporter to the link before and after the transporter is urged upwardly from either of the two upper levels.

- alignment of the characters with the mold slot, a connecting link interposed between the lever and the transporter, means for permitting relative movement between the transporter and the link when the descent of the transporter is arrested at either of the two upper levels, and means responsive to the operation of the mold disk for locking the transporter to the link before the transporter is urged upwardly from either of the two upper levels.
18. In a slug casting machine, the combination of a mold disk having a slotted mold, a vertically movable transporter for presenting a composed line of character bearing matrices before the face of the mold, means for arresting the descent of the transporter at one or another of three different casting levels, a cam operated lever for urging the transporter upwardly from any one of said levels to effect alignment of the characters with the mold slot, a connecting link interposed between the lever and the transporter, means for permitting relative movement between the transporter and the link when the descent of the transporter is arrested at either of the two upper levels, and yielding means responsive to the operation of the mold disk for locking the transporter to the link before the transporter is urged upwardly from either of the two upper levels.
19. In a slug casting machine, the combination of a vertically movable transporter for presenting a composed line of character bearing matrices before the face of a slotted mold, means for ar-

resting the descent of the elevator at one or another of two different casting levels, a cam operated lever for urging the transporter upwardly from either of said levels to effect alignment of the characters with the mold slot, a spring-loaded connecting link interposed between the lever and the transporter, and means for increasing the effective length of the link while maintaining the spring pressure at substantially the same value when the descent of the transporter is arrested at its upper level to an extent substantially equal to the distance between the two levels.

20. In a slug casting machine, the combination of a vertically movable transporter for presenting a composed line of character bearing matrices before the face of a slotted mold, means for arresting the descent of the elevator at one or another of two different casting levels, a cam operated lever for urging the transporter upwardly from either of said levels to effect alignment of the characters with the mold slot, a spring-loaded connecting link interposed between the lever and the transporter, and means for increasing the effective length of the link while maintaining the spring pressure at substantially the same value when the descent of the transporter is arrested at its upper level to an extent substantially equal to the distance between the two levels during the aligning operation and for restoring the link to its normal effective length before the line transfer operation.

GEORGE P. KINGSBURY.
